CLAIM

The ornamental design for a smart cooker as shown and described.

DESCRIPTION

FIG. 1 is a front, right perspective view of the smart cooker; FIG. 2 is a rear, left perspective view thereof; FIG. 3 is a top view thereof; FIG. 4 is a bottom view thereof; FIG. 5 is a left view thereof; FIG. 6 is a right view thereof; FIG. 7 is rear view thereof; and, FIG. 8 is a front view thereof.

The broken lines shown on the drawings depict portions of the smart cooker that form no part of the claimed design.
